HEAT EXCHANGER

Allen P. Livar, Dayton, Ohio, assignor to Chrysler Corporation, Detroit, Mich., a corporation of Delaware

Application November 25, 1941, Serial No. 420,401

8 Claims. (Cl. 126—99)

My present invention relates to the construction of warm air furnaces, space heaters or the like, having particular regard to the heat exchanger body thereof. My invention distinguishes from prior space heater and furnace heat exchangers in the utilization of relatively few parts of very simple construction.

The principal object of my invention is to provide a heat exchanger of relatively simple construction occupying as little space as possible and having a high rate of heat transfer.

Another object of my invention is to form a heat exchanger assembly of relatively simple parts comprising principally flat plates, easily formed cylindrical flue connectors and a plurality of identical tray-like members. By the use of a plurality of tray-like members I am able to build the heat exchanger body with the use of only one set of simple dies and forming fixtures, all other parts of the heat exchanger body being formed of sheets or cylindrical sections easily manufactured on standard sheet metal working machines.

A further object of my invention is to provide a type of heat exchanger assembly which can be formed in a plurality of different styles from a relatively few simple parts. Thus the sheet metal machines may be run continuously to stamp out and form a large stock of standard parts which can be interchangeably assembled to fill orders for heating equipment of widely different capacities and styles.

These and other objects and advantages of my present invention will be more readily ascertainable from an inspection of the following specification taken in connection with the accompanying drawings wherein like numerals refer to like parts throughout.

In the drawings,

Fig. 1 is a wide elevational view of a space heater embodying the present invention;

Fig. 2 is a front elevational view of the space heater;

Fig. 3 is a view in perspective of the assembled heat exchanger body;

Fig. 4 is a plan view of the heat exchanger body;

Fig. 5 is a vertical section taken substantially along line 5—5 of Fig. 4.

In the drawings there is disclosed in Figs. 1 and 2 a space heater of the gravity circulating, gas fired type, but it should be obvious from the following description that the heat exchanger body of the present invention may be used in

other types of furnaces. As disclosed, the space heater comprises an enclosing jacket 10 having grilles 11 at the lower portion thereof through which air is induced to travel by thermosiphonic action, the air passing over the heat exchanger body enclosed in the jacket 10 and into the space to be heated through the open top of the jacket 10, which may be suitably protected by a screen or grille (not shown). A pair of angle bars 12 extend from the front to the rear wall of the jacket and support the heat exchanger body 14 comprising the present invention.

The heat exchanger body, shown in Figs. 3, 4 and 5, comprises a firebox section 15 and a radiator section 16, said sections being formed as substantially rectangular enclosures of relatively great width and height with respect to their depth. The firebox section 15 comprises a tray-like member 17 having a flange 18 extending peripherally around its edge and lying in a plane substantially parallel to the bottom of the tray-like members, and a substantially identical tray-like member 19 having a flange 20 extending entirely around the periphery of its edge and lying in a plane substantially parallel to the bottom of the tray-like member. The firebox section is formed by placing the flanges 18 and 20 together and suitably uniting the flanges as by spot welding, seam welding, brazing, or the like. The two tray-like members thus form a firebox section having a front wall 22, rear wall 23, end walls 24 and 25, a top wall 26 and a bottom wall 27, the depth of the enclosure being substantially twice the depth of a single one of the tray-like members 17 or 19. The radiator section is formed from a single tray-like member 30, substantially identical to the tray-like members 17 and 19, and having a peripheral flange 31 substantially identical to the flanges 18 and 20 to which is united the edge of a flat sheet 32 forming the rear wall of the radiator section. The tray-like member 30 forms the front wall 33, the side walls 34 and 35, the top wall 36 and the bottom wall 37 of the radiator section.

The front wall 22 of the firebox section 15 is provided with an access opening to the edge of which is fastened a tubular member 40 through which extends the inspirator tube 41 leading to a gas burner 42 located within the firebox section. Supporting clips 43 may be welded to the surface of the tubular member 40 for the purpose of supporting a mounting plate 44 which is provided with a secondary air opening 45 and

inspection door 46, and which provides means for supporting the outer end of the inspirator tube 41 and the gas supply tube 47 together with such other instruments as are commonly associated with gas burners. The tubular member 40 is preferably of such diameter that the burner head 42 may be withdrawn and inserted therethrough and the bottom wall 27 of the firebox section 15 is preferably provided with a supporting member 48 upon which the burner head and inspirator tube are supported.

The firebox section is joined to the radiator section by means of spacer bars 50 welded or otherwise suitably attached to the upper corners of the two sections, and a pair of flue connectors 51 extending between the lower corners thereof, the bars 50 and connectors 51 being so aligned as to hold the two sections in horizontal and lateral alignment with the rear wall 23 of the firebox section spaced from and parallel to the front wall 33 of the radiator section, the two walls thus forming the side walls of a vertically extending air space between the two sections. The air which passes through the grilles 41 travels upward around all of the outer walls of the assembly and through the space between the two sections of the assembly.

In order to provide for efficient heat transfer between the flue gases within the sections and the air outside the sections, the firebox section is preferably provided with a pair of substantially vertical baffles 52 placed one at each side of the access opening, the baffles extending from the front wall 22 to the rear wall 23 and from the lower wall 21 to points spaced from the top wall 28 so as to provide openings between the top of the baffle and the top wall at each side of the space enclosed by the baffles. The baffles thus form a fire space within which the flame and flue gases travel upward and lateral flue spaces within which the flue gases travel downward into the connectors 51. A smoke outlet 53 is provided centrally of the upper portion of the rear wall 22 of the radiator section 16 so that the two streams of flue gases travel through the radiator section and unite while passing through the smoke outlet 53.

In order to induce circulation through the sections when a fire is first lit and the furnace sections are still cold, the lower front corners of the baffles 52 are provided with openings 55 such as by removing the corners of the baffle. Some of the cold air in the bottom of the lateral flue sections is thus caused to be drawn through the openings 55 and recirculated back into the flue openings by the inspirating effect of the flame. Substantially immediately thereafter the flue gases commence finding their way through the connectors 51 and the radiator section 16. Some of the flue gases will always recirculate through the openings 55, thus causing more uniform heating of the front wall 22 and of the bottom wall beneath the burner 42. The efficiency of the assembly is thus greatly enhanced and distortion of the walls of the section is materially reduced over what would be the case if the openings 55 were omitted.

The device illustrated in Figs. 1 to 5, inclusive, is a gas burning space heater having the usual appurtenances thereto, such as a draft diverter 56 mounted on the smoke outlet 53. However, it is to be appreciated that other types of burners may be mounted upon a suitably formed mounting plate 44 for attachment to the heat exchanger assembly comprising the present invention. It is also to be appreciated that the substantially

identical tray-like members 17, 19 and 30 may be formed by a deep-drawing, die-pressing operation, or that the same may be formed by other methods such as by notching and shaping a flat sheet and welding the corners of the side walls of the tray-like members.

I claim:

1. A warm air furnace heat exchanger comprising a firebox section and a radiator section, said sections being formed as substantially rectangular enclosures comprising front and rear walls of substantially the same size and side, top, and bottom walls, said sections being horizontally and laterally aligned with the rear wall of the firebox section spaced from the front wall of the radiator section to provide a vertical air space therebetween, a pair of substantially vertical baffles in said firebox section extending from the front wall to the rear wall thereof and from the bottom wall to points spaced from the top wall thereof, said baffles being laterally spaced from the center and the side walls of said firebox section to form a central fire space and lateral flue spaces, flue connectors extending rearwardly from the rear wall of said firebox section adjacent the lower portion of each of said flue spaces to the lower corners of the front wall of said radiator section, and a smoke outlet at the upper, central portion of said radiator section.

2. A warm air furnace heat exchanger comprising a firebox section and a radiator section, said sections being formed as substantially rectangular enclosures comprising front and rear walls of substantially the same size and side, top, and bottom walls, said sections being horizontally and laterally aligned with the rear wall of the firebox section spaced from the front wall of the radiator section to provide a vertical air space therebetween, a pair of substantially vertical baffles in said firebox section extending from the front wall to the rear wall thereof and from the bottom wall to points spaced from the top wall thereof, said baffles being laterally spaced from the center and the side walls of said firebox section to form a central fire space and lateral flue spaces, flue connectors extending rearwardly from the rear wall of said firebox section adjacent the lower portion of each of said flue spaces to the lower corners of the front wall of said radiator section, and a smoke outlet at the upper, central portion of said radiator section.

3. A warm air furnace heat exchanger comprising a firebox section and a radiator section, said sections being formed as substantially rectangular enclosures comprising front and rear walls of substantially the same size and side, top, and bottom walls, said sections being horizontally and laterally aligned with the rear wall of the firebox section spaced from the front wall of the radiator section to provide a vertical air space therebetween, a pair of substantially vertical baffles in said firebox section extending from the front wall to the rear wall thereof and from the bottom wall to points spaced from the top wall thereof, said baffles being laterally spaced from the center and the side walls of said firebox section to form a central fire space and lateral flue spaces, flue connectors extending rearwardly from the rear wall of said firebox section adjacent the lower portion of each of said flue spaces to the lower corners of the front wall of said radiator section, and a smoke outlet at the upper, central portion of said radiator section, each of said baffles having an opening therethrough adjacent the lower, front corners thereof permitting recirculation of some of the flue gas from the flue spaces into the fire space whereby more evenly to heat the entire front wall of the firebox section.

4. A warm air furnace heat exchanger comprising a firebox section and a radiator section, said sections being formed as substantially rectangular enclosures comprising front and rear walls of substantially the same size and side, top, and bottom walls, said sections being horizontally and laterally aligned with the rear wall of the firebox section spaced from the front wall of the radiator section to provide a vertical air space therebetween, a pair of substantially vertical baffles in said firebox section extending from the front wall to the rear wall thereof and from the bottom wall to points spaced from the top wall thereof, said baffles being laterally spaced from the center and the side walls of said firebox section to form a central fire space and lateral flue spaces, flue connectors extending rearwardly from the rear wall of said firebox section adjacent the lower portion of each of said flue spaces to the lower

corners of the front wall of said radiator section, and a smoke outlet at the upper, central portion of said radiator section, each of said baffles having its lower, front corners cut away so as to provide communication between the lower, front portions of said flue spaces and said fire space permitting recirculation of some of the flue gas from the flue spaces into the fire space whereby more evenly to heat the entire front wall of the firebox section.

4. A warm air furnace heat exchanger comprising a firebox section and a radiator section, said sections being formed as substantially rectangular enclosures comprising front and rear walls of substantially the same size and side, top, and bottom walls, said sections being horizontally and laterally aligned with the rear wall of the firebox section spaced from the front wall of the radiator section to provide a vertical air space therebetween, a pair of substantially vertical baffles in said firebox section extending from the front wall to the rear wall thereof and from the bottom wall to points spaced from the top wall thereof, said baffles being laterally spaced from the center and the side walls of said firebox section to form a central fire space and lateral flue spaces, flue connectors extending rearwardly from the rear wall of said firebox section adjacent the lower portion of each of said flue spaces to the lower corners of the front wall of said radiator section, and a smoke outlet at the upper, central portion of said radiator section, said firebox section comprising a pair of substantially identical, tray-like members each including an upstanding wall forming one of the first mentioned walls and pairs of opposed walls projecting from said upstanding wall toward the other of said members respectively forming portions of said side walls and said top and bottom walls, the projecting wall forming portions of one of said members and the corresponding projecting wall forming portions of the other of said members having their edges abutted and joined together throughout their extent.

5. A warm air furnace heat exchanger comprising a firebox section and a radiator section, said sections being formed as substantially rectangular enclosures comprising front and rear walls of substantially the same size and side, top, and bottom walls, said sections being horizontally and laterally aligned with the rear wall of the firebox section spaced from the front wall of the radiator section to provide a vertical air space therebetween, a pair of substantially vertical baffles in said firebox section extending from the front wall to the rear wall thereof and from the bottom wall to points spaced from the top wall thereof, said baffles being laterally spaced from the center and the side walls of said firebox section to form a central fire space and lateral flue spaces, flue connectors extending rearwardly from the rear wall of said firebox section adjacent the lower portion of each of said flue spaces to the lower corners of the front wall of said radiator section, and a smoke outlet, at the upper, central portion of said radiator section, said firebox section comprising a pair of substantially identical, tray-like members each including an upstanding wall forming one of the first mentioned walls and pairs of opposed walls projecting from said upstanding wall toward the other of said members respectively forming portions of said side walls and said top and bottom walls, the projecting wall forming portions of one of said members and the corresponding projecting

wall forming portions of the other of said members having their edges abutted and joined together throughout their extent, and said radiator section comprising a third tray-like member substantially identical to the tray-like members forming said firebox section.

6. A warm air furnace heat exchanger comprising a firebox section and a radiator section, said sections being formed as substantially rectangular enclosures comprising front and rear walls of substantially the same size and side, top, and bottom walls, said sections being horizontally and laterally aligned with the rear wall of the firebox section spaced from the front wall of the radiator section to provide a vertical air space therebetween, a pair of substantially vertical baffles in said firebox section extending from the front wall to the rear wall thereof and from the bottom wall to points spaced from the top wall thereof, said baffles being laterally spaced from the center and the side walls of said firebox section to form a central fire space and lateral flue spaces, flue connectors extending rearwardly from the rear wall of said firebox section adjacent the lower portion of each of said flue spaces to the lower corners of the front wall of said radiator section, and a smoke outlet at the upper, central portion of said radiator section, said firebox section comprising a pair of substantially identical, tray-like members each including an upstanding wall forming one of the first mentioned walls and pairs of opposed walls projecting from said upstanding wall toward the other of said members respectively forming portions of said side walls and said top and bottom walls, the projecting wall forming portions of one of said members and the corresponding projecting wall forming portions of the other of said members having flanges protruding from the edges thereof placed in face-to-face relationship and welded to each other throughout their extent.

7. A warm air furnace heat exchanger comprising a firebox section and a radiator section, said sections being formed as substantially rectangular enclosures comprising front and rear walls of substantially the same size and side, top, and bottom walls, said sections being horizontally and laterally aligned with the rear wall of the firebox section spaced from the front wall of the radiator section to provide a vertical air space therebetween, a pair of substantially vertical baffles in said firebox section extending from the front wall to the rear wall thereof and from the bottom wall to points spaced from the top wall thereof, said baffles being laterally spaced from the center and the side walls of said firebox section to form a central fire space and lateral flue spaces, flue connectors extending rearwardly from the rear wall of said firebox section adjacent the lower portion of each of said flue spaces to the lower corners of the front wall of said radiator section, and a smoke outlet at the upper, central portion of said radiator section, said firebox section comprising a pair of substantially identical, tray-like members each including an upstanding wall forming one of the first mentioned walls and pairs of opposed walls projecting from said upstanding wall toward the other of said members respectively forming portions of said side walls and said top and bottom walls, the projecting wall forming portions of one of said members and the corresponding projecting wall forming portions of the other of said members having flanges protruding from the edges thereof placed in face-to-face relationship and welded to each other

throughout their extent, and said radiator section comprising a third tray-like member substantially identical to the tray-like members forming the firebox section and a flat sheet having its periphery welded to the flange of said tray-like member throughout its extent.

8. A warm air furnace heat exchanger comprising a firebox section and a radiator section, said firebox section having one wall thereof adjacent to and spaced from the adjacent wall of said radiator section to provide a vertical air space between said sections, a pair of substantially vertically disposed baffles in said firebox section extending from said one wall to the wall

portion opposite thereto and from the bottom of said firebox section to points spaced from the top thereof, said baffles being so spaced laterally one from the other and from the respective laterally adjacent wall portion of said firebox section as to respectively provide a generally central fire space and lateral flue spaces, flue connectors extending from said one wall of said firebox section adjacent the lower portion of each of said flue spaces to the lower portion of said radiator section providing communication between said sections, and a smoke outlet at the upper, mid-portion of said radiator section.

ALLEN P. LIVAR.
